(57) **CLAIM**

The ornamental design for a combined key chain and dispenser, as shown.

DESCRIPTION

FIG. 1 illustrates a front elevation view of a combined key chain and dispenser;

FIG. 2 illustrates a rear elevation view of FIG. 1;

FIG. 3 illustrates a top plan view of FIG. 1;

FIG. 4 illustrates a bottom plan view of FIG. 1;

FIG. 5 illustrates a left side plan view of FIG. 1; and,

FIG. 6 illustrates a right side plan view of FIG. 1.

The broken line showing of environmental matter is for illustrative purposes only and forms no part of the claimed design.
